UNITED STATES PATENT OFFICE.

HENRY CHARLES JENKINS, OF LONDON, ENGLAND.

ELECTROLYTIC CELL.

1,150,370.

Specification of Letters Patent. Patented Aug. 17, 1915.

Application filed November 4, 1914. Serial No. 870,240.

To all whom it may concern:

Be it known that I, HENRY CHARLES JENKINS, a subject of the King of England, residing at 804 Salisbury House, London Wall, 5 London, England, associate Royal School of Mines, engineer, whose post-office address is 804 Salisbury House, London Wall, London, England, have invented certain new and useful Improvements in Electrolytic 10 Cells, of which the following is a specification.

The present invention relates to electrolytic cells for the decomposition of solutions, such as the aqueous solutions of alkaline 15 chlorids and nitrates, and relates more particularly to cells in which the decomposition is effected without the use of a porous diaphragm separating the liquids lying around the cathode and anode respectively.

20 The invention is specially applicable to cells of the so called bell type, and in which aqueous solutions of alkaline chlorids are electrolyzed, for the production of caustic alkali and chlorin, or where the caustic alkali produced by electrolysis is converted 25 into carbonate by supplying carbonic acid gas in the neighborhood of the cathode.

Under the present invention a definite 30 vertical displacement of the electrolyte in stratified layers between the anode and the cathode is attained.

In the following description of the invention the anode is supposed to be that electrode contained within the bell, but the external connections may for some usages be 35 reversed so that this electrode become the cathode without altering the character of the invention.

The invention consists in an electrolytic 40 cell of the bell type in which the liquid to be treated is introduced to the bell containing the anode in such a manner as to maintain a concentrated condition of the liquid at the anode surfaces, the liquid introduced 45 displacing liquid in the bell, either upward to a draw off device within the bell, from which draw off device the liquid flows over a weir, or downward toward the lower edge of the bell. The flow in one or other of 50 the two directions may be intermittent, or the incoming stream of electrolyte may be divided into two parts.

The invention further consists in controlling 55 the division of the flow of electrolyte toward the electrode in such cell by adjusting a weir.

The invention also consists in a cell of the type described, in which the levels of the liquids are caused by difference of pressure to be different inside and outside the bell, 60 the liquid being drawn off by overflowing into a pipe opening at the higher level, and returned by a pipe below the level of the liquid.

The invention further consists in a cell of the type described having an automatic valve adapted to close the pipe by which the gas is drawn off under suction from the interior of the bell when the bell is removed 65 from the cell.

The invention also consists in the improved apparatus for electrolysis herein-after described.

Referring to the accompanying drawings Figure I is a diagrammatic view of the 70 general arrangement of the cell and subsidiary tanks. Fig. II is a section in echelon across a series of pairs of cathodes and anodes. The left hand half of the figure shows two such pairs, as would be seen by a section in the plane A. B. in Figs. III and IV, while the right hand half of the figure shows the draw off channel for liquid and the channel with automatic valve within the bell for gas seen in section and in elevation respectively near to the plane C D in Fig. III and Fig. IV. Fig. III is a section on the plane E F of Fig. II, and at right angles to the earlier figures. Fig. IV is a section parallel to Fig. III but in the 75 plane G H.

In carrying the invention into effect according to the example illustrated there is provided a suitably formed external cell or bath (1) of metal earthenware or other 80 suitable material the particular material selected depending on the chemical composition of the material electrolyzed, and being selected for its resistant properties to such material. In the example shown in Figs. II, III and IV it has an iron outer framework with a filling and inner surfaces of non-conducting material, but in some cases the walls of a cell may act as an electrode. Conducting cathodes (2) and anodes (3) are 85 provided. The cathodes (2) may be formed of suitable metal, and built up in any suitable manner to allow gas evolved at their surfaces to escape into an inverted tray of any suitable material (4) from which the 90 gases pass by a pipe (5) and stopcock if desired to a collecting pipe (6) outside the 95

cell. Bus bars (7) and (8) are provided by which to connect the series of one or more pairs of anodes and cathodes to a suitable source of electrical energy.

5. If desired means may be provided for introducing carbonic acid gas or other gas to the electrolyte.

If desired the cathodes may be formed hollow and gas or liquid either hot or cold 10 may be forced through them to regulate the temperature.

The anode (3) is situated within a bell (9) of earthenware or other suitable non-conducting material preferably made impervious to liquids. This bell, as illustrated, is freely open on its underside. It may 15 however be partially closed either by a suitable grid or porous diaphragm. The bell projects for a convenient distance into the 20 liquid, and separates this into two portions.

As illustrated the anode is attached firmly to the bell, and projects into its interior, an air-tight electrical connection or connections being made to the anode bus bar (7) 25 through holes at the top of the bell. Within the bell there are provided pipes (10), (11) rising from the floor of the outer cell (1). The pipes (10) rise to near the top of the 30 bells and are sometimes provided with valves (12), operated in this form by levers (13) that have bifurcated ends which take under 35 opposite sides of the rims of the valves (12) and rock on a shoulder loosely fitted in a curved recess in a fixed part of the cells adjacent to the pipes 10. Each lever (13) has a projecting arm (14) adapted to come 40 in contact with the top of the bell when the latter is placed in position in the cell, so that on placing the bell in position the lever (13) is operated and the valve (12) lifted. When the bell is raised the valve (12) automatically closes by reason of its own weight or otherwise.

The pipe (10) by which the gases are 45 drawn off leads to a draining chamber (15) from which liquid is drawn off by the pipe (16) to the sump (17) while the gases are drawn off by the pipe (18). A diminished pressure relative to that existing on the 50 surface of the electrolyte outside the bell is thus always maintained in the vessel (15) and thus within the bell (9).

In order to regulate the temperature and the conditions as regards saturation of the 55 electrolyte, the draw off pipe (11) is provided, leading to the interior of the bell, and which may be fitted with an enlarged mouth, situated at a convenient height above the level of the liquid in the outer cell. This 60 level is somewhat determined by the difference of pressure maintained in the chamber (15). The draw off pipe (11) is connected outside the cell to a small tank (19) which is provided with a weir 20 which can 65 be set at any desired height, the liquid over-

flowing the weir passing into a sump or channel 21 from which it is drawn off by a pump to suitable devices for heating, saturating or other treatment, such as removal of gases, precipitation of products or neutralization. The third vertical pipe 22 leading to the interior of the bell serves for the purpose of admitting electrolyte. This pipe opens into the bell at a level a little above 70 its lower edge, and on to the active surface 75 of the anode and is flared at its end 23, and provided with a suitably shaped obstructing piece 24 to direct the liquid in substantially a horizontal sheet across the bell. By suitably arranging the size or shape of these 80 obstructing pieces, the quantity of liquid passing to each bell of the cell can be varied so that uniform conditions can be maintained in a number of different bells of a single cell. With this arrangement if extra 85 liquid is placed in a second subsidiary tank 25 connected to the pipe 22, the level there will be raised, and the liquid will flow under the bell in a more or less flat sheet, and displace liquid from the upper surface of the 90 bell. The concentrated condition of the liquid at the electrode within the bell is maintained by from time to time supplying to the second tank 25 freshly concentrated 95 liquid obtained by evaporation or other means or by keeping a supply of undissolved salt in the supply tank. Where a regulated temperature of the contents of the bell is required, the liquid between the two 100 outside tanks may be heated as by steam or water pipes, or by electrical resistance or otherwise. Such subsidiary apparatus is indicated in the diagram Fig. I as at 26 but part or all of this may also be for convenience placed in another part of the 105 circulating system as at 25 or 22. Freshly concentrated or heated brine or other electrolyte may be added to the system as represented by the supply pipe 27 to the 110 sump 21.

The quantity of liquid circulated may be regulated by a dipper wheel or pump or other suitable means and delivered in any predetermined manner, and rate, and suitable pumps may be provided for elevating the liquid between the sump 21 and the tank 25 all such measuring and pumping gear being indicated by the device 28 in the diagram.

The rapidity of passage of the electrolyte through the cells may be regulated further by introducing a frictional resistance such as for instance baffles in the supply pipe. One such baffle is found in the suitably 115 shaped obstructing piece 24.

The alkali or other liquid product of electrolysis is drawn off by overflow from the pipe 29 into the channel 30.

The current of regenerated electrolyte 120 opposed to the direction of the diffusion of 125

the liberations, as from an inlet such as 23, will assist in the operation of the cell. The electrolyzed liquid may be withdrawn from the outer cell either continuously or intermittently as desired. The amount so drawn off may further be varied by varying the difference of pressure between the inside and the outside of the bell, or by varying the level of the outlet weir 20 or by varying 10 the quantity of liquid supplied.

In order to prevent loss of heat, the cell may be coated with non-conducting material, and when the amount of heat that would be carried off by conduction or which 15 is required for chemical reaction is excessive, and beyond the capacity of the regulators, I may pass a small current of steam through the base of the cell such as by pipes 31 provided for that purpose.

20 Having fully described my invention, what I claim and desire to secure by Letters Patent is:—

1. An electrolytic cell of the indicated type comprising an external cell, an electrode therein, an overflow pipe to said cell, a bell-shaped top located in the upper part of the cell with its lower open mouth below the overflow therefrom, an electrode within said bell, a liquid supply pipe discharging 25 immediately below the electrode in the bell, a liquid draw-off pipe opening in the said bell above the lower open mouth of said bell, a gas discharge pipe opening in the upper part of the bell, and means for withdrawing 30 the gas from the bell through said gas pipe.

2. An electrolytic cell of the indicated type comprising an external cell, an electrode therein, an overflow pipe to said cell, a bell-shaped top located in the upper part 40 of the cell with its lower open mouth below the overflow therefrom, an electrode within said bell, a liquid supply pipe discharging immediately below the electrode in the bell, a liquid draw-off pipe opening in said bell 45 above the lower open mouth of said bell, a

tank connected to said liquid draw-off pipe, an adjustable weir in said tank, a gas discharge pipe opening in the upper part of the bell, and means for withdrawing the gas through said gas pipe.

3. An electrolytic cell of the indicated type comprising an external cell, an electrode therein, an overflow pipe to said cell, a bell-shaped top located in the upper part of the cell with its lower open mouth below the overflow therefrom, an electrode within said bell, a liquid supply pipe discharging immediately below the electrode in the bell, a liquid draw-off pipe opening in said bell above the lower open mouth of said bell, a tank connected to said liquid draw-off pipe, an adjustable weir in said tank, a gas discharge pipe opening in the upper part of the bell, an automatic valve on the upper end of said gas pipe, and means for withdrawing 65 the gas from the bell through said gas pipe.

4. An electrolytic cell of the indicated type comprising a cell and a bell-shaped top thereto each containing one of the electrodes, and a liquid supply pipe discharging 70 below the electrode in the bell and having a flared outlet.

5. An electrolytic cell of the indicated type comprising a cell and a bell shaped top 75 thereto each containing one of the electrodes, a liquid supply pipe discharging below the bell electrode and having a flared outlet, and an obstructing piece located in said outlet to restrict the flow and cause it 80 to stream laterally through the bell adjacent to the bell electrode.

In testimony whereof I have hereunto set my hand in presence of two subscribing witnesses this 23 day of October 1914.

HENRY CHARLES JENKINS.
